UNITED STATES PATENT OFFICE

CLAIBORNE W. GOOCH, JR., AND ALCIDAS J. MARCOTTE, OF LYNCHBURG, VIRGINIA,
ASSIGNORS TO UNITED CIGARETTE MACHINE COMPANY, INC., OF LYNCHBURG,
VIRGINIA, A CORPORATION OF VIRGINIA

BUTTING BLADES FOR TOBACCO STEMMING MACHINES

Application filed April 23, 1931. Serial No. 532,302.

The present invention relates to improved butting blades for tobacco stemming machines which are adapted to take the place of the butting devices as fully described in U. S. 5 Patent No. 1,212,441 of January 16, 1917.

It is an object of the present invention to utilize the blades for cleaning both the butts and for stemming, and it may be used in a stemming machine similar to the one shown 10 in U. S. Patent No. 1,538,662 of May 19, 1925.

It is a further object of this invention to provide the blades so that each individual blade will be rigid; furthermore, each blade is provided with a plurality of individual 15 rigid arms having cutting edges.

Further objects will be apparent from the following description taken in connection with the accompanying drawing, in which:

Figure 1 is a side view of two sets of 20 operating butting blade assemblies,

Fig. 2 is an end view of the blade assemblies and leaf gripper, and

Fig. 3 is a side view of one of the blades.

It is, of course, obvious that such blade 25 assemblies can be used in any specific type of stemming machine desired, as, for instance, in those disclosed in the U. S. patents mentioned in the foregoing and also in the stemming machine disclosed in U. S. Patent 30 No. 1,268,392, dated June 4, 1918.

The blade assemblies or units are constructed in any suitable manner; for example, as shown in Figs. 1 and 2, a sleeve 4 is provided having a shoulder 14 at one end and being 35 threaded at the other end to accommodate the clamping nut 6 have cut-out portions 7 which are adapted to receive a suitable wrench to tighten the stemming devices 3 and spacing rings 2 on sleeve 4. Sleeve 4 is fur-

ther provided with a suitable setscrew 5 adapted to clamp the sleeve securely on an operating shaft, not shown. As shown in Fig. 1, the periphery of the blades of one 45 assembly projects a slight distance beyond the periphery of the blades of the other set and the blades are arranged in staggered relation.

Each device, as shown in Fig. 3, is provided with a plurality of rigid blades 8 which 50 are radially arranged and any suitable num-

ber can be used, but, in the preferred construction, as shown on the drawing, there are six arms equally spaced from one another, that is, 60° apart. At the extreme end of each arm there is an approximately flat surface, 9 which can be of any desired width; and the blades are of sufficient thickness to be rigid laterally and as a matter of fact in all directions and can be made of any suitable material. Each device has a central perforation 10 to accommodate the sleeve on which the assemblies are mounted and each blade has a cutting edge or, as a matter of fact, two cutting edges 13 on opposite sides of the leading face of the blade relative to the 55 rotation of the device.

As disclosed in the patents referred to, the butting blades are adapted to remove a portion of the leaf from the thickened or butt end of the stem so that thereafter such stems 60 can be gripped by suitable grippers to remove the portion of the stem desired. For the purpose of removing the leaves from the thickened or butt end of the stem, they are held by any suitable conveying means, such as by belts 11 mounted on wheels 12. These belts carry the leaves along through the butting blades, and, as shown in Fig. 2, the tobacco leaves move straight forward while the blade assemblies 1 move in opposite directions, that is, the upper blades of Fig. 2 65 move in a clockwise direction and the lower blades move in a counterclockwise direction, as shown by the arrows. The arrow in Fig. 1 indicates the path of travel of the tobacco 70 leaves through the butting blades and this is, of course, carried out by means of the conveyor belts.

We claim as our invention:—

1. A leaf-stripping assembly for tobacco stemming and butting machines, comprising a plurality of stemming devices, each device having a plurality of rigid blades.

2. A leaf stripping unit for tobacco stemming and butting machines, comprising a plurality of rigid blades.

In testimony whereof, we affix our signatures.

CLAIBORNE WATTS GOOCH, JR.
ALCIDAS JOSEPH MARCOTTE.
